UNITED STATES PATENT OFFICE.

JOSEPH A. FRAUENHEIM, OF ZELIENOPLE, PENNSYLVANIA.

DESIGN FOR A WASHSTAND.

No. 37,691.

Specification for Design.

Patented Nov. 21, 1905.

Application filed September 25, 1905. Serial No. 280,087. Term of patent 7 years

To all whom it may concern:

Be it known that I, JOSEPH A. FRAUENHEIM, a citizen of the United States, residing at Zelienople, in the county of Butler and State of Pennsylvania, have invented a new, original, and ornamental Design for Washstands, of which the following is a specification, reference being had to the accompanying drawing, forming part thereof.

The figure is a perspective view of a washstand showing my new design.

I claim--

The ornamental design for a washstand as shown.

JOSEPH A. FRAUENHEIM.
